(57) **CLAIM**

The ornamental design for a dust box with water tank for cleaning appliance, as shown and described.

DESCRIPTION

3. Dust box with water tank for cleaning appliance
4. Dust box with water tank for cleaning appliance

3.1 : Front

3.2 : Back

3.3 : Left

3.4 : Right

3.5 : Top

3.6 : Bottom

3.7 : Perspective

3.8 : Perspective

3.9 : Perspective

4.1 : Front

4.2 : Back

4.3 : Left

4.4 : Right

4.5 : Top

4.6 : Bottom

4.7 : Perspective

4.8 : Perspective

4.9 : Perspective

(Continued)

Reproductions 3.1 to 3.9 are six orthographic projection views and three perspective views of a third dust box with water tanker for cleaning appliance; and reproductions 4.1 to 4.9 are six orthographic projection views and three perspective views of a fourth dust box with water tank for cleaning appliance.
